FERDINAND J. HOHNHORST, AND FERDINAND J. KROEGER, OF COVINGTON, KENTUCKY

MECHANISM FOR TRUING AND DRESSING GRINDING WHEELS OF CENTERLESS GRINDERS

Application filed March 14, 1930. Serial No. 435,823.

Our invention relates to mechanism for truing and dressing grinding wheels, such as emery wheels, including carborundum wheels and the like, in centerless grinding machines, in which the work is rotated by peripheral contact with the peripheries of opposed grinding wheels rotating at different speeds.

The grinding wheels employed in grinding metals and similar hard substances in machines of this character are composite grinding wheels containing comminuted or finely divided emery, carborundum or other cutting medium and a suitable bond, suitably bound together as a composite mass, the fineness of the grains of the cutting medium determining the coarseness or fineness of the grinding.

It is the object of our invention to provide novel means for truing or dressing the grinding surface of the grinding wheel or wheels in a machine of this character; further, to provide a composite abrading wheel and means whereby to present the composite abrading wheel to the grinding surface of the grinding wheel under the hood of the grinding wheel; further, to provide novel means for supporting the abrading wheel; further, to provide novel means for traversing the support of the abrading wheel while projecting through the hood of the grinding wheel; further, to provide an abrading wheel and means for mounting the same at an angle to the periphery of the grinding wheel under the hood of the grinding wheel; and, further, to provide novel mounting means for the abrading wheel extending through a slot in the hood of the grinding wheel for permitting lateral adjustment of the abrading wheel across the face of the grinding wheel and a slide movable with said mounting for maintaining closed relation of said slot to prevent the passage of grinding dust and particles therethrough.

The invention will be further readily understood from the following description and claim, and from the drawings, in which latter:

Fig. 1 is a side elevation of an exemplifying

centerless grinding machine embodying our invention, partly broken away.

Fig. 2 is a plan view of the same, partly broken away.

Fig. 3 is an axial section of our improved device, taken on the line 3—3 of Fig. 2.

Fig. 4 is a cross-section showing an exemplified bearing means for the abrading wheel of our improved device taken on the line 4—4 of Fig. 3.

Fig. 5 is a cross-section taken in the plane of the line 5—5 of Fig. 3, with the closing plate removed.

Fig. 6 is a cross-section showing the clamping means for the sleeve, taken on the line 6—6 of Fig. 2; and,

Fig. 7 is an axial section, partly broken away, showing a modification of our improved device.

The exemplified centerless grinding machine comprises a frame 11 which has a bearing 12 in which the shaft 13 of a grinding wheel 14 rotates. The shaft is suitably driven, and the grinding wheel is suitably releasably secured to the shaft. This grinding wheel is the main grinding wheel of the couple. The auxiliary grinding wheel of the couple is exemplified at 15, and is releasably secured to a shaft 16 journaled in a bearing 17 on a slide 18 adjustable and movable in guides 19 on the main frame toward and from the grinding wheel 14. The means for adjusting and moving the auxiliary grinding wheel are not shown because wellknown.

A support 21 for the work is located in the space between the grinding wheels. The structure and form of the support is dependent on the work to be ground.

A hood 25 is received about the grinding wheel 14, and a hood 25' is received about the grinding wheel 15. These hoods encompass the major portions of the peripheries of the grinding wheels.

Truing or dressing means are provided for the respective grinding wheels. These truing or dressing means are respectively mounted on the respective hoods and project through said hoods. They may be of similar construction, although one may differ from the other in non-essential details. The abrading

means for the main grinding wheel are shown and described in detail, similar parts for the abrading means for the auxiliary grinding wheel being indicated by similar but primed reference numerals.

6 In the present exemplification the grinding wheel 14 has the major portion of the grinding wheel encompassed by the hood 25 which is fixed to the frame, the hood 25' of the auxiliary grinding wheel being mounted on the slide 18.

10 The hood 25 is provided with a bracket 26 to which a guide 27 is secured, the guide having a guideway 28 on which a slide 29 is arranged to move laterally with relation to the plane of the grinding wheel 14.

15 A screw-shaft 31 is journaled in a bearing 32 on the guide and is held endwise therein, the screw-rod being threaded in a threaded nut 33 fixed on the slide. A hand-wheel 34 is fixed to the screw-rod for rotating the same and thereby moving the slide laterally.

20 The slide is provided with a bearing 35 in which a sleeve 36 is adjustable axially. The sleeve is arranged to be clamped in adjusted positions in the bearing by means of a clamp-shoe 30 clampingly acted on by a clamp-bolt 37. This sleeve is preferably movable axially in said bearing toward and from the grinding-wheel in the hood for locating the abrading wheel 38 in approximate position with relation to the grinding wheel.

25 The sleeve is provided with a bore 39 in which there is a shank 40 of a mounting for the abrading wheel. This shank is adjustable axially in the sleeve, as by providing the shank with an axially threaded portion 41, in which a feed-screw 42 is threaded. The

30 feed-screw has a journal-portion 43 in an axial bearing 44 at the outer end of the sleeve, and is provided with a hand-wheel 45 for rotating the feed-screw. The feed-screw is held endwise in its bearing by locating the bearing between a collar 46 on the feed-screw and the hub of the adjusting wheel 45. The bearing is secured to the end of the sleeve, as by means of screws 47.

35 The inner end of the shank is provided with means for securing the abrading part thereto. These are exemplified as comprising a fork 51 having a hood 52. The fork is provided with bearings 53. An axle 54 is secured in said bearings, as by means of clamp-bolts 55 securing the caps 56 of said bearings to the fork 51 of said shank or mounting for the abrading wheel.

40 A shell 61 has ball-bearings 62, 63, 64, 65, therein, arranged in pairs, the outer raceways of the pairs being separated by a ring 66. A plug 67 is threaded in the shell and clamps the outer raceways and ring between a shoulder 68 in the shell and said plug.

45 The axle is provided with a flange 69 located between the inner raceways of the respective pairs of ball-bearings. Annular

50 spaces 70 are located between the outer ends of said inner raceways and the end wall 71 and said plug 67 respectively. Said wall and plug are provided with inner peripheries 72 making close joint connection with the outer periphery of said axle.

55 The axle is provided with a passage 74 having a branch 75 connecting with the space 76 in said shell and with a branch 77 connecting with the passage 78 in one of the bearings 53, the outer end of the latter passage being provided with a lubricant fitting 79 through which lubricant may be introduced through the passages and into said hollow of the shell for lubricating the bearing.

60 The abrading wheel is a composite abrading wheel comprising grains of emery, carborundum or other cutting medium of suitable fineness, dependent on the fineness of the work to be done, and a suitable bond, 55 suitably bound together as a composite mass, preferably of a texture much harder than the texture of the grinding wheel, and of substantially smaller diameter than the grinding wheel.

65 The abrading wheel is rotated by peripheral contact with the periphery of the grinding wheel. It is preferably held in a plane at an angle to the plane of the grinding wheel.

70 The grinding wheel during operation becomes impregnated with particles of dirt or metal from the work being operated on and become comparatively glossy and thereby loses its grinding effect, its granular structure also becoming dull at the grinding face, thereby reducing its grinding or polishing properties.

75 By means of our invention particles of dirt and metal are removed from the grinding surface of the grinding wheel by coaction of the rotary abrading wheel therewith whereby to clear the recesses and pores in the grinding surface, and the particles or grains in the abrading surface are sharpened.

80 In order to maintain the abrading wheel at an angle with relation to the grinding wheel there is a spline groove and key connection 81 between the shank 40 and the sleeve 36.

85 The shank passes through a slot 82 in the hood. A plate 83 normally closes said slot and is arranged to slide laterally in a guide 84 on said hood. The plate is provided with an outward bulge 85 in which there is a hole 86. The inner end of the sleeve is received through said hole in said plate, and is adjustable axially in said hole by axial adjustment of the sleeve in its bearing 35. The sleeve normally closes said hole so as to prevent the passage of dust and dirt through said hole. The bulge accommodates the fork 51, the hood 52, and the abrading wheel and other parts mounted in the fork, throughout the various adjustments of the abrading wheel.

When it is desired to true or to dress the grinding wheel the sleeve 36 is adjusted axially in its bearing 35 and in the hole 85 for approximately positioning the abrading wheel 5 with relation to the grinding wheel, the sleeve being clamped in such position in said bearing. The hand-wheel 45 is then turned for obtaining the proper contact between the abrading wheel and the grinding wheel. 10 The grinding wheel being rotated by its usual power drive causes rotation of the abrading wheel by peripheral contact therewith. The relative positioning between the abrading wheel and the grinding wheel causes a wiping action between the periphery of the abrading wheel and the periphery of the grinding wheel for truing and dressing the latter.

During such operation the abrading wheel 20 is moved laterally across the width of the grinding wheel by manipulation of the hand-wheel 34, whereby the slide 29 and the abrading wheel 38 are shifted laterally on the hood. This lateral shifting also causes lateral movement of the plate 83 in its guide, the plate throughout all its adjustments maintaining the slot 82 closed.

If desired, a composite abrading stub or pencil 91 made of composition similar to that 30 of the abrading wheel may be mounted in a socket 92 in the inner end of a shank 140 and fixed therein by a set-screw 93. This stub or pencil may have a contour at its contact end with the grinding wheel of suitable 35 shape for imparting a desired peripheral contour to the grinding wheel, if it is desired to impart a shape to the grinding wheel other than cylindrical. Such an arrangement is illustrated in Fig. 7, in which parts are shown similar to those above described but raised to the series 100.

Our improved device is simple in construction and operation and provides means whereby the dressing or truing of the grinding wheel may be quickly accomplished and dispenses with the use of expensive diamonds which have been heretofore employed for the purpose.

Having thus fully described our invention, 50 what we claim as new, and desire to secure by Letters Patent, is:

In a machine of the character described, the combination of a grinding wheel, a hood therefor, an abrading wheel operatively located between said hood and said grinding wheel, a mounting for said abrading wheel comprising a fork, a sleeve and a shank; said fork fixed to the inner end of said shank, a guide on said hood, a laterally movable slide on said guide, means on said slide for securing said sleeve thereto, bearing means for said abrading wheel on the inner end of said fork operatively located between said hood and said grinding wheel, said shank located in 55 said sleeve, means holding said shank non-

rotative in said sleeve for holding and maintaining said fork and said bearing means for said abrading wheel at an angle to the plane of said grinding wheel, means for adjusting said shank in said sleeve, said hood provided with a slot, and a cover plate for said slot having slide connection with said hood, said cover plate provided with an upwardly extending bulge, the crown portion of said bulge provided with a hole through which said mounting extends, said bulge forming an enclosure above and about said inner end of said shank, said angularly positioned fork, said bearing means and said abrading wheel, said cover plate movable laterally on said hood with said mounting, and said cover plate with its bulge maintaining said slot in closed relation throughout the lateral movements of said abrading wheel.

In testimony whereof, we have hereunto signed our names.

FERDINAND J. HOHNHORST.
FERDINAND J. KROEGER.
